J. G. JUDD

WIRE GRIPPER

Filed March 8, 1924

Inventor
John G. Judd
By Harry De Wallace

Attorney

Patented Dec. 30, 1924.

UNITED STATES PATENT OFFICE.

JOHN G. JUDD, OF DETROIT, MICHIGAN.

WIRE GRIPPER.

Application filed March 8, 1924. Serial No. 697,804.

To all whom it may concern:

Be it known that I, JOHN G. JUDD, a citizen of the United States, residing at Detroit, in the county of Wayne and State of Michigan, have invented certain new and useful Improvements in Wire Grippers, of which the following is a specification.

This invention relates to improvements in wire grippers, or "come-alongs", designed for use in connection with the erection of telephone, telegraph, power-transmission, fence wires, and the like, and has for its object to provide a novel and simple portable device of the class, by which wires of different size may be positively gripped and stretched taut, without requiring any change or setting of the working parts. A further object is to provide a light and durable wire gripper comprising a pair of self-adjusting members, which are pivotally mounted in a strong metal body, and which are arranged to positively grip the opposite sides of the wire; the said members being normally held in the closed or idle position by suitable tension means. And a further object is to provide a wire gripper which may be readily and quickly snapped on to a wire, by pressing the device against the wire with sufficient force to spread the gripping members; the said members being rotatably supported in socket-bearings, which share with the pivot bolts all of the strains, and at the same time render the action of the members more positive and less liable to let loose and chafe or otherwise injure the wires.

I attain these objects by the means set forth in the detailed description which follows, and as illustrated by the accompanying drawing, in which—

Figure 1 is a top plan view of the complete device; showing the gripping members in the idle position. Fig. 2 is a side elevation of the same. Fig. 3 is a horizontal section, taken on line 3—3 of Fig. 2; showing the device gripping a wire. And Fig. 4 is respectively a top-face, and an edge view of one of the gripping members.

In the drawing, 2 represents generally the body of the gripper, which comprises a relatively broad hollow head 2', and a flat tapering handle 2", the latter having an opening 2" near its free end, by means of which a pulling rope or chain (not shown) of any suitable length, may be secured. The top portion of the head 2' is preferably divided longitudinally by an upwardly facing

groove 2", running centrally through the head, into which the wires, as 3, to be gripped and stretched, may be disposed. The groove 2" is preferably broad enough to accommodate wires up to about one-half inch in diameter. The open top of the head 2', at the opposite sides of the groove 2", is closed by similar caps or plates 4, which are preferably held in place by rivets 4'. These plates form with the head lateral chambers or pockets 5—5', in which the gripping members, as 6—6' are pivotally disposed, by means of bolts 7, which pass loosely through the base 2" and the gripping members, and are then screwed into threaded openings 4" of the caps 4. The members 6—6' are substantially pear-shaped, and their enlarged portions or lobes 6" are preferably formed truly concentric to the pivots 7, and operatively fit into correspondingly curved wall portions 2" of the head, thereby providing ball-and-socket bearings, which tend to prevent the gripping members from being forced outwardly when the strains resulting from the gripping and straightening of the wires are exerted against the bolts 7. The opposite exposed edges of the members 6—6', which project into the groove 2", are correspondingly serrated, as at 6", for affording a positive grip of the wire 3 (see Fig. 3). The members 6—6' are normally held in the idle or closed position shown in Fig. 1, by springs 8, the corresponding ends 8" of which engage slots 6" of the members, while their opposite ends 8" are supported by the outer lateral walls of the head, as best seen in Fig. 3. The gripper may be applied to any portion of the wires; although Figs. 2 and 3 show the device applied near the free end of the wire 3. Where wires of heavy gage are being erected, a block-and-tackle (not shown) is usually attached to the handle 2", for suitably stretching the wires. Owing to the novel design and the extremely simple construction and arrangement of the device, my gripper complete, for ordinary use, weighs but a trifle more than one pound, and may be readily carried in a lineman's pocket, or may be suspended from his belt, like his pliers and other small tools.

When the gripper is placed in position on a wire, the taking up of the slack of the wire is effected by pulling the gripper towards the right, as shown by the arrows in Figs. 1, 2 and 3. This movement of the gripper tends to rotate the members 6—6' to-

wards each other and tightens the grip on the wire in proportion to the stress of the pull.

Having thus described my invention, 5 what I claim, is—

1. A wire gripper comprising a body having a hollow head divided into similar facing chambers and a reduced handle, by which the body is supported and moved 10 when stretching a wire, a pair of oppositely facing gripping members pivoted in said chambers, the facing edges of said members projecting beyond said chambers and said members being serrated for positively gripping a wire, the serrated edges of said members adapted to contact with each other when the wire is removed; and tension means for normally and resiliently holding said members in the closed position.
  2. A device of the class described, comprising a hollow head and a tapering handle by which the head is supported during the stretching of a wire, said head having similar chambers separated by a central longitudinal groove which is formed in the top face of the head in line with the handle, a rotatable gripping member pivotally mounted in each chamber, the lobe of each member frictionally engaging a concentric wall-portion of the head, and tension means for normally forcing the members towards each other.
  3. A wire gripper and slack take-up, comprising a hollow head and a perforated handle by which the head is supported while stretching a wire as well as when
- being carried by an operator, said head being divided into two chambers by means of a central longitudinal groove adapted to receive and guide the wire in line with said handle, similar gripping members disposed in said chambers having serrated edges which project into said groove, individual caps for closing said chambers, bolts for pivotally supporting said members, and for holding said caps in place, the outer walls of said head being formed with sockets which receive portions of said members and relieve the strain on the bolts, and springs for yieldingly holding said serrated edges normally in contact.
4. A wire stretcher consisting of a combined head and handle by which the head is supported and operated, the head having its top face formed with a normally open cavity and with a longitudinal slot for supporting a wire during the stretching, the bottom of the slot and the top side of the handle being in a common plane, the said slot dividing the said cavity into facing sockets, wire gripping members pivotally mounted in said sockets, the facing edges of said members being serrated and said edges adapted to contact at the center of said slot when the device is removed from the wire, and similar caps overlying the open sides of said slot at the opposite sides of said slot, and pivoting means passing through said caps, said members, and the bottom walls of the sockets.

In testimony whereof I affix my signature.
JOHN G. JUDD.
